UNITED STATES PATENT OFFICE

2,641,360

SPRING FOR HINGED CASES

Ellison S. Irelan, Elgin, Ill., assignor to Illinois
Watch Case Co., a corporation of Illinois

Application April 6, 1950, Serial No. 154,392

9 Claims. (Cl. 206—41)

1

This invention relates to a spring for hinged cases and more particularly a spring which presses against the portions of a hinged case by virtue of torsion as distinguished from a helical coil action, and which completely eliminates any irregularities or gaps in the hinge arrangement of the case in which it is used.

One feature of this invention is to provide a new and improved means for urging the portions of a hinged case to open position. Another feature is to provide a spring means which is positioned entirely within the case so as to present a more pleasing case exterior, particularly along the hinge line. Another feature is the provision of a spring means which may be installed in a hinged case after the case is assembled. Another feature is the provision of a spring means which may be removed from the case for replacement with a like spring without removing parts of the case from their assembled position. Still another feature is the provision of a spring means which may be installed in existing hinged cases to replace a broken spring or one which has lost its resiliency. Other advantages and features will be apparent from the description of an embodiment of this invention illustrated in the accompanying drawings, in which:

Fig. 1 is a plan view of a double row cigarette case with the spring means of this invention installed therein;

Fig. 2 is a sectional view taken substantially along line 2—2 of Fig. 1;

Fig. 3 is a plan view of the spring of this invention removed from the case;

Fig. 4 is a side elevational view of the spring, looking upwardly from the bottom of Fig. 3; and

Fig. 5 is an end view of the spring shown in Fig. 3, looking from the left thereof.

Hinged cases such as compacts, cigarette cases and the like have previously been constructed with a hinge of the multiple pintle bearing or "piano" type connecting two portions of the case so that it may be opened and closed. In some cases it is desirable that a spring or other means be provided to spring open the case upon the disengagement of a latch or other fastening means. In cigarette cases, a presser bar or retaining bar swingably mounted on the hinge of the case was resiliently urged toward the cigarette receiving compartment to hold cigarettes therein even though the case be open. Such resiliency was provided by using a coil spring wound about the pin of the case hinge and having its ends respectively abutting the presser bar and the opposite portion of the case, or a second presser bar. In using a coil spring, the spring had to be assembled along with the case since the hinge pin had to pass through both the

2

pintle bearings of the case portions and the coiled portion of the spring. Moreover, portions of the hinge sections or pintle bearings had to be left off of both case sections to enable such a coil spring to surround the hinge pin, resulting in an irregularity in the hinge line and an exposed spring spoiling the back appearance of the case. This invention provides a spring means which forms no part of the hinge of the case, and which may be installed in the case after the latter has been assembled.

The invention will be described with reference to the particular embodiment illustrated in the drawings which comprises a double row cigarette case having two mating halves connected by a multiple pintle bearing hinge.

In Figs. 1 and 2 the case comprises two similar mating halves 10 and 11, each having a presser bar 12, 13 for retaining cigarettes in each half of the case. The halves 10 and 11 are connected by a pin 14 passing through pintle bearings 15 which are integral with the half 10, and pintle bearings 16 integral with the half 11. The presser bar 12 is swingably mounted on the pin 14 by pintle bearings 17 and the presser bar 13 is likewise mounted on the pin 14 by pintle bearings 18. The case halves may be held in closed position by a latch 19 which is provided with a release member 20 for opening the case.

The spring means of this invention comprises a torsion bar 25 which is removably mounted on the presser bars adjacent the hinge of the case. The bar 25 has similar halves reversed in position and joined in the center by a portion adapted to extend over the hinge of the case in which the bar is used. The end portions 26a, 26b of the torsion member comprise a hooked portion 27a, 27b with an inturned extremity 28a, 28b. As seen in Fig. 1, the hooked portion 27a grasps the edge 13a and the extremity 28a bears against the face of the presser bar 13. The opposite end portion 26b grasps the edge 12a with its hooked portion 27b and the extremity 28b thereof bears against the presser bar 12.

Extending inwardly from the end portions 26a, 26b are substantially straight portions 30a and 30b which are joined by a center arcuate portion 34. When installed in the case, as best seen in Fig. 1, the substantially straight portions 30a, 30b extend respectively under the presser bars 13, 12, along the hinge of the case. The center arcuate portion 34 extends over the hinge to connect the straight portions of the torsion member. When the case is open a major portion of the torsion member is hidden from view with only the center portion 34 and end portions 26a, 26b appearing above the presser bars. The end portions 26a, 26b, and the center portion 34 may be rigid, permitting the spring action to be entirely

from torsion of the substantially straight portions of the spring.

In the process of manufacturing cigarette cases, such as illustrated in the accompanying drawings, the two portions of the case and the presser bars may be assembled by inserting the pin 14 through the respective pintle bearings 15, 16, 17 and 18. After the case is thus assembled the spring torsion member may be inserted in its proper position by merely hooking the end portions 26a, 26b over the edges of the respective presser bars. Thus the torsion member of this invention may be utilized to render again operative, a case in which a coil spring has broken or lost its tension. The invention may also be used in cases for other purposes which do not have presser bars such as 12 and 13 by providing an anchor portion on each half of the case for attaching the end portions 26a, 26b of the torsion member.

While I have shown and described one embodiment of the invention, it is to be understood that it is capable of many modifications. Changes, therefore, in the construction and arrangement may be made without departing from the spirit and scope of the invention as pointed out in the appended claims.

I claim:

1. In a double row cigarette case having mating halves hingedly connected, cigarette retaining means comprising: a pair of presser bars pivotally mounted on the hinge, each bar being adapted to retain cigarettes in one half of the case; a torsion member mounted on said presser bars adjacent the hinge to urge the presser bars apart toward respective halves of the case, said torsion member having end portions each hooked over an edge of respective presser bars with the extremity thereof engaging the presser bar in opposition to the torsion stress in the member and a substantially straight portion extending under the presser bar from each end portion toward the center of the case and a center arcuate portion extending over the hinge to connect said straight portions.

2. In a double row cigarette case having a hinge connecting mating halves of the case, a cigarette retaining means comprising: a pair of presser bars pivotally mounted on said hinge; a spring tensioning member urging said presser bars toward respective halves of the case, said spring tensioning member having end portions respectively engaging an edge of the respective presser bars and a substantially straight portion extending from each end portion toward the center of the case and lying under the presser bars adjacent said hinge and an arcuate center portion connecting said straight portions and extending over the hinge whereby said presser bars are urged toward respective halves of the case by torsion of the spring tensioning member.

3. In a double row cigarette case having mating halves hingedly connected, a cigarette retaining means comprising: a presser bar over each half of the case pivotally mounted on said hinge; a torsion member adapted to urge said presser bars apart toward respective halves of the case, said torsion member having end portions each hooked over the edge of respective presser bars adjacent the hinge and a substantially straight portion extending under a presser bar from each end portion toward the center of the case and a center portion extending over the hinge to connect said straight portions.

4. In a double row cigarette case having a

hinge connecting mating halves of the case, a cigarette retaining means comprising: a pair of presser bars pivotally mounted on the hinge, each presser bar being adapted to retain cigarettes in one half of the case; a single torsion member removably mounted on said presser bars to urge the presser bars apart and toward respective halves of the case, said torsion member having two opposite similar portions each lying under a presser bar so as to be hidden from view when the case is open.

5. In a double row cigarette case having a hinge connecting mating halves of the case, a cigarette retaining means comprising: a pair of presser bars pivotally mounted on the hinge; a torsion member removably mounted on the presser bars adjacent the hinge to urge the presser bars apart and toward respective halves of the case, said torsion member having end portions hooked to engage an edge of said presser bar and a torsion portion between the end portions.

6. In a double row cigarette case having a hinge connecting mating halves of the case and a pair of presser bars pivotally mounted on the hinge, means for urging the presser bars toward respective halves of the case comprising: a torsion member engaging the presser bars adjacent the hinge, said torsion member having a center portion extending over the hinge and a substantially straight portion underlying each presser bar and extending from the center portion toward the sides of the case and end portions hooked over the outer edges of the presser bars.

7. Apparatus of the character claimed in claim 6 in which at least the substantially straight portions of said torsion member have an elasticity permitting torsion thereof to urge the presser bars apart.

8. In a cigarette case having a hinge permitting the case to be opened and closed, means for retaining cigarettes in the case comprising: a presser bar swingably mounted on said hinge and adapted to extend over the cigarette receiving compartment; a torsion member urging said presser bar toward the cigarette receiving compartment, said torsion member having an end portion attached to an edge of the presser bar and a substantially straight portion extending along the hinge from said end portion and an arcuate portion extending from the straight portion over the hinge.

9. In a container having two portions hingedly connected to permit opening and closing thereof, means for urging the portions of the container to open position comprising: a torsion member having a pair of substantially straight portions extending generally in the direction of the hinge and adjacent to opposite sides of the hinge, said torsion member having end portions bearing against respective portions of the container independently of the hinge, and a center arcuate portion extending over the hinge to connect said straight portions.

ELLISON S. IRELAN.
